[57] CLAIM

The ornamental design for a detachable pour spout attachment for a paint can or the like, substantially as shown and described.

DESCRIPTION

FIG. 1 is a side elevational view of a pour spout attachment for a paint can or the like showing my new design, with a portion of a paint can being shown in broken lines for illustrative purpose only;

FIG. 2 is a top plan view;

FIG. 3 is a rear elevational view;

FIG. 4 is a front elevational view;

FIG. 5 is a bottom plan view; and

FIG. 6 is a sectional view taken on the line 6—6 of FIG.

2.

*Fig. 1.**Fig. 2.**Fig. 3.**Fig. 4.**Fig. 5.**Fig. 6.*
